DUMPING APPARATUS

Original Filed June 12, 1918 3 Sheets-Sheet 3

UNITED STATES PATENT OFFICE.

RICHARD RADDATZ, OF MILWAUKEE, WISCONSIN, ASSIGNOR, BY MESNE ASSIGNMENTS, TO WOOD HYDRAULIC HOIST & BODY COMPANY, OF DETROIT, MICHIGAN, A CORPORATION OF MICHIGAN.

DUMPING APPARATUS.

Application filed June 12, 1918. Serial No. 239,505. Renewed January 30, 1925.

To all whom it may concern:

Be it known that I, RICHARD RADDATZ, a citizen of the United States, residing at Milwaukee, in the county of Milwaukee and 5 State of Wisconsin, have invented certain new and useful Improvements in Dumping Apparatus, of which the following is a specification, reference being had to the accompanying drawing, forming a part 10 thereof.

This invention relates to dumping apparatus and the object of the invention is to improve the construction of dumping apparatus in the manner to be hereinafter 15 described and claimed.

In the operation of dumping a load by applying force to a platform, the force required to tip the platform is variable because, as the center of gravity of the load is 20 raised, less force is required to tip the platform as the center of gravity of the load approaches a vertical line passing through the fulcrum or pivotal point.

The apparatus to be hereinafter described 25 does not require excessive power to start the dumping operation, maintains the power with substantially no variations and fluctuations while tipping the platform to the dumping position and can be arranged in a 30 very compact form.

For simplicity of illustration and description the invention is illustrated as applied to a motor truck but such illustration is not intended to limit the application of the invention to use with motor trucks.

Referring to the drawings which accompany this specification and form a part hereof, which drawings illustrate an embodiment of this invention, and on which drawings the 40 same parts are designated by the same reference characters wherever they may appear in each of the several views, Fig. 1 is a side elevation of a motor truck, parts being shown in section; Fig. 2 is a plan view of 45 parts of the truck; Fig. 3 is a side elevation, on an enlarged scale, of parts shown by Fig. 1; Fig. 4 is a vertical cross-section taken on the line 4—4 on Fig. 2, looking in the direction indicated by the arrows; and Fig. 5 is a 50 vertical cross-section taken on the line 5—5

on Fig. 2, looking in the direction indicated by the arrows.

Referring to the drawings, the reference numeral 1 designates a motor truck which is provided with a body 2, hereinafter called the platform. The platform 2 is illustrated as being fulcrumed or pivoted to the frame of the truck by a pivot, or pivots, 3. If the platform 2 is uniformly loaded, the center of gravity of the load will lie in a vertical line half way between the ends and the sides of the platform and will be at a greater or less distance from the platform depending upon the amount of the load in volume, for the same material, or the specific gravity of the load of the same weight as compared with a load of different specific gravity. The center of gravity of a load is indicated on the drawings by the reference letter α and it will be apparent from an inspection of Fig. 1 of the drawings that the center of gravity of the load approaches a vertical line passing through the fulcrum or pivotal point of the platform as the platform is tipped to the dumping position shown in dotted lines. It is apparent from an inspection of Fig. 1 of the drawings that if the front end of the platform 2 were to be lifted, the greatest power would have to be exerted at the commencement of the lift and the power required to complete the lift would diminish progressively as the tipping increased.

This invention provides apparatus, for tipping a platform, of such a character that a substantially constant power motor exerts its power through associated mechanism to apply the greatest force to the platform at the commencement of the tipping movement and to apply progressively diminishing force to the platform as the tipping movement is continued. The drawings illustrate simple but effective mechanism and apparatus for accomplishing the desired result. The motor exerts its power through a lever which tips the platform with a varying leverage. The lever is designated by the reference numeral 4 and a plurality of such levers may be employed, as shown by the drawings, to better distribute the strains and stresses. Antifriction devices 5 may be interposed be- 100

tween a lever 4 and the platform 2 and, as a matter of convenience and simplicity of construction, it is preferred to secure a single antifriction device 5 to the platform 2 over a lever 4. This construction provides a variable or differential fulcrum between a lever and the platform. The levers 4 are pivoted on fixed fulcrums 6 and it will be readily seen from an inspection of Figs. 1 and 3 of the drawings that rocking a lever 4 on its fulcrum 6 will tip the platform 2 and that, as the platform 2 is tipped, the antifriction roller 5 will bear against the lever 4 at points more remote from the fulcrum 6 so that the lever 4 is a differential lever for transmitting the power of the motor to the platform 2. The motor may be of any suitable, preferred type or construction. The drawings illustrate a fluid pressure motor as a suitable and preferred type for use in connection with vehicles, though it is to be understood that the specific type or construction of motor to be employed is not material to this invention. The motor is illustrated as composed of a cylinder 7 which is provided with a piston 8 and a piston rod 9. The piston rod 9 passes loosely through an aperture 10 in a cross-head 11 and a ball and socket joint is shown as formed by a depression in the cross-head and the rounded end of a nut 12 on the end of the piston rod. This construction allows the cross-head to be thrown out of true alignment without causing the piston rod to bind, if parts of the frame of the truck bend. It is, of course, immaterial whether the piston rod is arranged to pull or push or whether two or more cylinders are employed and so arranged that their piston rods pull and push the cross-head. The cross-head 11 is shown as provided with anti-friction devices, or rollers 13, which act as slides or supports and rest upon tracks 14. Links 15 and 16, which are shown as formed to straddle the levers 4, are pivotally connected with the levers 4 and with the cross-head 11. The pivots 17, which pivot the links 15 and 16 to the levers 4, may be placed forward of the pivots 6 and forward of the cross-head 11 and below the cross-head so that the force exerted by the motor upon the levers 4 will be exerted with a differential effect depending on the angles which the links 15 and 16 make with the levers 4. It is immaterial what fluid is used in the cylinder 7 but, for the purpose of this description, it will be assumed that an incompressible fluid, such as oil, is used and that the front end of the cylinder is the power or operating end and that the rear end of the cylinder serves as an oil reservoir. A pump 18 can draw oil from the rear end of the cylinder and force it under pressure between the front head of the cylinder and the piston 8. The pump 18 draws the oil from the rear end of the cylinder through a pipe

19 and forces it into the front end of the cylinder through a pipe 20.

The pump 18 is illustrated as driven by the shaft 21, sprocket wheels 22 and 23 and sprocket chain 24 from a shaft 25 which is rotated by the engine, not shown, of the truck. A clutch 26 and a shifting lever 27 provide means for starting or stopping the pump 18 at will whenever the shaft 25 is being rotated. A by-pass 28 is illustrated as connecting pipes 19 and 20 between the pump 18 and the cylinder 7. A valve 29 controls the thoroughfare through the by-pass 28 and is normally held closed by the spring 30. The rod 31 is connected with the valve 29 and passes through a hole in a clip 32 which is secured to the cross-head 11. A nut 33, which may be backed by a lock nut, on the screwthreaded end of the rod 31 provides adjustable means for positively opening the valve 29 when the platform has been tipped to a selected, predetermined angle. Before the platform has been tipped to the selected, predetermined angle, the valve 29 may be opened manually and held open by the rod 34 which can be moved by the lever 35.

Heretofore it has been assumed that the center of gravity of the load maintained its position with respect to the platform as the platform was being tipped. This is the case until the platform has been tipped to such an angle that the load commences to slide in whole or in part. When the load slides in whole or in part, the center of gravity of the load shifts towards a vertical line through the fulcrum or pivotal point and less power is required to complete the tipping of the platform. To avoid any possibility of the platform being tipped too far, or overthrown, any suitable stop mechanism can be provided as, for example, a hook 36 on the platform and a pin 37 on a lever 4. The ends of the levers 4 may be rounded or beveled off as indicated by the reference numeral 38 to provide run-offs for the anti-friction devices 5.

The operation of the apparatus will be evident from the foregoing description. It may be added, however, that the operator has entire control of the platform by means of the valve 29. For example, he can manipulate the valve 29 to hold the platform tilted to any angle or to decrease the velocity of the movement of the platform as it approaches the dumping position or he can ease the platform, loaded or unloaded, back to its initial position, as will be readily understood, because, if the pump 18 is in operation, the effect of the pump on the motor can be varied by by-passing more or less of the fluid.

The reference numeral 39 designates a check valve which opens towards the cylinder 7 and prevents the fluid seeping through the pump 18 when the pump is not being

operated and the platform, loaded or unloaded, is raised.

The hook 36 and pin 37, or equivalent mechanism, can be used as a positive stop to stop the tipping of the platform with a jerk so as to dislodge sticky material such as asphalt, for example, or material which has locked or bridged.

The apparatus can be arranged in an exceedingly compact and mechanically efficient manner as, for example, when used upon a motor truck as illustrated by the drawings the downward stresses upon the pivots or fulera 6 can be transmitted directly to an axle or to the frame between the points where it is supported by the springs. This construction avoids the liability of springing or bending the frame members of the truck as will be readily understood.

20 What is claimed is:

1. In dumping apparatus, the combination with a tiltable platform of a lever pivotally supported below the platform and adapted to be swung upwardly in the same general direction as that in which the platform tilts, a link pivotally connected with said lever and inclined upwardly therefrom and towards the pivotal point of said platform, means to guide the upper end of said link in a predetermined path, and means connected with the upper end of said link to swing said lever up to tilt said platform.

2. In dumping apparatus, the combination with a tiltable platform of a plurality of 35 levers pivotally supported below the plat-

form and adapted to be swung upwardly in the same general direction as that in which the platform tilts, links pivotally connected with said levers and inclined upwardly therefrom and towards the pivotal point of said 40 platform, a cross-head connecting the upper ends of said links, means to guide the cross-head in a predetermined path, and motor mechanism for moving said cross-head.

3. In dumping apparatus, the combination of a tiltable platform provided with a fulcrum near one end thereof and also provided with a fixed fulcrum or bearing for a lever, a lever provided with a fulcrum intermediate the fulera of the platform, a 50 cross-head located between the lever and the platform, a connection between the cross-head and the lever, and a substantially constant power motor for moving the cross-head to tilt the lever and the platform in the 55 same general direction of movement.

4. In dumping apparatus, the combination of a horizontal cylinder, provided with a piston and piston-rod, horizontal guides, a cross-head, a tiltable platform above the 60 cylinder and provided with a fixed bearing or fulcrum for a lever, a lever provided with a fulcrum below the cross-head and bearing against the fixed fulcrum on the platform, an inclined link connecting the cross-head 65 with the lever, and means to force fluid into the cylinder to tilt the platform.

In witness whereof I hereto affix my signature.

RICHARD RADDATZ.
